(57) **CLAIM**

The ornamental design for a electric fly swatter, as shown and described.

DESCRIPTION

FIG. 1 is a perspective view of the electric fly swatter showing my new design;

FIG. 2 is a another perspective view of the electric fly swatter showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a partial enlarged view of portion 9 in FIG. 1

FIG. 10 is a partial enlarged view of portion 10 in FIG. 2; and,

FIG. 11 is a folding state diagram.
